UNITED STATES PATENT OFFICE.

HARRY M. BROADWELL, OF PLAINVILLE, CONNECTICUT, ASSIGNOR TO TRUMBULL ELECTRIC MFG. CO., OF PLAINVILLE, CONNECTICUT, A CORPORATION OF CONNECTICUT.

QUICK-BREAK SWITCH.

1,314,302.

Specification of Letters Patent. Patented Aug. 26, 1919.

Application filed August 22, 1918. Serial No. 250,911.

To all whom it may concern:

Be it known that I, HARRY M. BROADWELL, a citizen of the United States of America, residing at Plainville, Connecticut, have invented a new and useful Quick-Break Switch, of which the following is a specification.

This invention relates to quick break switches and particularly to those of the knife blade type, the objects of the invention being in general to provide a simple and effective form of connection between the movable switch element and the operating member therefor which will impart the necessary snap action to the switch element on the breaking of the circuit.

Other objects are to provide a device of this character which will be relatively inexpensive and which, while compact in form, will be quite powerful so as to effect a quick, positive movement.

In accordance with my invention, the movable switch element is connected with the operating member therefor by means of helical switch-throwing springs and these springs are disposed on an incline between the movable switch element and the operating member in such a way as to enable the use of longer and therefore more powerful and effective springs than could be the case if such springs were directly connected straight across the shortest distance between the operating members and movable switch element.

The invention also embodies a novel construction of bracket forming a positive lost motion connection between the operating member and movable switch element and serving also as the anchorage for the throwing springs.

In the accompanying drawings I have disclosed the invention embodied in one of its practical commercial forms, this with the idea however, that the form may be varied in different respects without departure from the true spirit and scope of the invention.

In said drawings:

Figure 1, is a cross sectional view of a double-throw switch having the features of my invention incorporated therein, the switch being shown in the intermediate or neutral position.

Fig. 2, is a similar view with the switch in circuit-closed condition and the operat-

ing member shown in the act of shifting the movable switch element to the open-circuit position.

Figs. 3 and 4 are broken sectional views of the switch as viewed from the right in Figs. 1 and 2.

In the illustration the movable switch element is shown in the form of a blade 5 pivoted at 6 and having oppositely extending arms 7 and 8 adapted for engagement with the oppositely disposed contact clips 9 and 10 respectively, said parts being mounted on a suitable insulating base 11.

The switch operating member consists in the illustration, of an arm 12 over-standing the cross bar 13 which connects the switch blades substantially parallel thereto, said arm having an angularly bent end portion 14 engaging with the hub 15 of the pivoted switch operating handle 16.

The quick break mechanism comprises a pair of coiled or helical springs 17 arranged on divergent angles and connected between the movable switch element and the over-standing operating arm 12. These springs are shown connected at their outer ends with dependent lugs or tangs 18 struck downward from the metal of the operating arm, and at their inner ends with lugs 19 struck upward from the opposite side edges of brackets 20 secured by the screws 21 to the cross bar 13.

The inclined disposition of these springs between the cross bar and the substantially parallel over-lying operating arm enables the use of longer and hence more resilient and powerful springs than could be the case if such springs were connected directly or straight across the shortest distance between the cross bar and the over-standing operating arm. This provides a powerful switch-throwing mechanism in compact form.

The bracket to which the throwing springs are anchored is formed with oppositely disposed outwardly projecting arms, 100 or abutments 22, extending to opposite sides of the operating arm 12. These arms form a positive lost motion connection between the operating arm and movable switch elements as will be apparent particularly from Figs. 1 and 2.

In Fig. 1, with the operating arm in the intermediate or neutral position, the switch

is yieldingly held by the springs in an intermediate inactive position. When it is desired to engage the switch blades 8 with the contacts 10, the operating arm 12, which, 5 as shown, is pivoted substantially concentric to the movable switch blades, is rocked in a right-handed direction, the engagement of the operating arm 12 with the up-standing arm 22 of the bracket providing 10 a positive connection by which the switch blades can be forced firmly into engagement with the respective contacts. To break the circuit, the handle is operated to shift the operating arm 12 in a left-handed direction, which carries the same into engagement with the up-standing arm 22 disposed to the left of the same. A positive connection is now afforded whereby the movable switch blades can be positively drawn 15 from engagement with contacts 10. As the switch blades are on the point of leaving said contacts, the helical springs which have been placed under tension during this movement (see Fig. 2), react and snap 20 the blades quickly from engagement with the contacts, the lost motion between the operating arm and the bracket arms allowing for this snap movement.

In the case of a large or heavy switch, 30 such as a three bladed switch, a plurality of pairs of switch-throwing springs with their accompanying brackets may be provided, substantially as is indicated in Figs. 3 and 4.

35 My invention provides, it will be seen, a simple and reliable quick break mechanism and one which may be readily applied to switch constructions now in use.

I claim:—

40 1. In a quick break switch, the combination with a movable switch element and a switch operating arm pivoted in substantially concentric relation, of a pair of helical switch-throwing springs each connected 45 at one end with said switch operating arm and each connected at the opposite end with

the movable switch element arm and movable switch member and both inclined with respect to the arm and the movable switch element to occupy a smaller space between 50 the operating arm and switch element whereby to enable the use of the springs of greater length than the shortest distance between the operating arm and movable switch member. 55

2. In a quick break switch, substantially parallel switch blades, a cross bar connecting the free ends of the same, a switch operating arm overlying said cross bar, a bracket secured to said cross bar and 60 relatively inclined helical switch-throwing springs extending from said bracket to the switch operating arm.

3. In a quick break switch, substantially parallel switch blades, a cross bar connecting the free ends of the same, a switch operating arm overlying said cross bar, a bracket secured to said cross bar, spaced upstanding arms carried by said bracket and disposed at opposite sides of the operating arm and relatively inclined helical switch-throwing springs extending from 70 said bracket to the switch operating arm.

4. In a quick break switch, substantially parallel pivoted switch blades, a cross bar 75 connecting the free ends of said switch blades, a pivoted operating member having an arm over-standing and substantially parallel to said cross bar, a bracket secured on said cross bar having separated upstanding arms extending into position at opposite sides of the over-standing operating arm and provided with anchorage lugs at opposite edges thereof and helical switch-throwing springs engaged with said anchorage lugs 80 and connected with the over-standing operating arm, said springs being inclined relative to the cross bar and operating arm to enable the use of springs longer than the shortest distance between the cross bar and 85 operating arm. 90

HARRY M. BROADWELL.
